UNITED STATES PATENT OFFICE

LOUIS A. M. PHELAN, OF ELKHART, INDIANA, ASSIGNOR, BY MESNE ASSIGNMENTS, TO MINNEAPOLIS-HONEYWELL REGULATOR COMPANY, OF MINNEAPOLIS, MINNESOTA A CORPORATION OF DELAWARE

ELECTRICAL APPARATUS

Application filed November 25, 1927. Serial No. 235,434.

The present invention relates to electrical apparatus and it has special reference to electrical contact-making devices comprising spaced electrodes that are sealed into a closed container and are adapted to be brought into electrical conducting relation with one another through the agency of a movable conducting body, preferably a fluid such as mercury, likewise disposed in said container and which, on being tilted, is instrumental in performing the circuit-closing and circuit-opening functions of the device.

More particularly the invention refers to an electrical contactor device of the character indicated above, which will operate for long periods of time and serve to make and break comparatively large amounts of current without deterioration in any of its parts.

The present invention pertains to an electrical contactor device, as described above, which, if desired, may comprise a cylindrical elongated tube, preferably in the form of a tubular container, that serves to house electrodes and a body of conducting fluid such as mercury, the latter being adapted to bridge the electrodes within the tube. The tube is preferably disposed when installed, to occupy normally a position neighboring on the horizontal and is suitably supported so that it may be tilted in either direction and thus allow the conducting fluid to flow into and out of circuit-making position at the expense of very little energy.

The present invention also comprises such an arrangement of the parts within the electrical contactor device that the electrical current passing through the same will be interrupted by the breaking of the continuity of conducting fluid, instead of a break in contact between such fluid and a solid conductor.

Furthermore, the present invention also provides an internal dam in the container that houses the electrodes and the conducting fluid, so that the conducting fluid will be broken up into two unequal parts, both of which remain in electrical contact with solid conductors. This dam is preferably inclined on one side so that the conducting fluid when it breaks apart will do so rapidly, while the larger part of the fluid will roll away from

the break so that any arc that might start will be quickly stopped.

A further object of the invention is to provide an internal dam for the conducting fluid made of a heat-insulating material or refractory material, so that the heat caused by the arc at the point of severance of the conducting fluid will be prevented from rupturing the container or the internal dam. This heat-insulating dam is retained in position within the container by any convenient means such as by making it sufficiently resilient to enable it to expand slightly or "spring" into place within the container; by providing grooves having expansible resilient material disposed therein; or by cementing the same to the internal walls of the container.

A further object of this invention is to provide a contactor device of the type indicated above that will be simple and economical to construct and will possess a long life even when subjected to considerable quantities of electric current at substantial voltages.

Further objects will appear upon reference to the following description and accompanying drawings, in which:

Figure 1 is a vertical sectional view of one modification of the device embodying the present invention;

Fig. 2 is a similar view showing a further modification;

Fig. 3 is a side elevation of one of the inserts or dams, showing one means of securing the same within the housing;

Fig. 4 is a vertical sectional view of another modification of the device embodying the present invention;

Fig. 5 is a vertical sectional view of still another modification;

Fig. 6 is an end view of one form of dam employed in the interior of the container shown in Fig. 5;

Fig. 7 is a vertical sectional view of another modification of the device embodying the present invention, in which case the dam has a special shape;

Fig. 8 is a vertical sectional view of still a further modification of the device; and

Fig. 9 is a perspective view of a dam as shown in Fig. 8.

Referring to Figs. 1, 2, 4, 5, 7, and 8, the device preferably comprises, in a general way, a cylindrical and elongated container 11 made preferably of an insulating material, such as glass, housing a pair of electrodes or contact members 12 and 13, which are disposed apart within the container 11, and are adapted to make electrical contact with a conducting fluid, which may comprise mercury, 14 and 14-a. In order to ensure the breaking up of the mercury into two portions when the current is to be interrupted, a dam or obstruction 15 is placed within the tube, being preferably so positioned that a large body of mercury 14 and a smaller body of mercury 14-a will be produced when the container is slightly tilted in one direction, which, in the drawings, would be to the right. On slightly tilting the container to the left, the larger body of mercury 14 will rise over the dam 15, and, uniting with the smaller body of mercury 14-a, will establish an electrical conducting path between the electrodes 12 and 13.

In order to make it easy for the mercury to rise over the dam when the circuit is to be closed, the dam is preferably made inclined on the side toward the larger body of mercury. In order to bring about a sudden break in the current, however, when the same is to be interrupted, the dam is substantially right-angled at the side toward the smaller body of mercury 14-a. Thus, when the container is tilted to the right, the mercury will pass through or over the dam 15, the body of mercury becoming attenuated as the greater part of it flows to the right. Finally, and suddenly, the column of mercury still connecting the two portions 14-a and 14 will break apart, and the portion 14 will thus be isolated. By reason of the inclined sides of the dam 15, the mercury will rapidly roll away from the smaller portion 14-a, so that any electric arc produced during the break will be but of short duration. The end portion of the electrode 13 extends within the dam 15. The foregoing construction ensures that the electric arcs on the breaking of the circuit through the contactor will always occur over the dam 15 and thus preclude the arcs from damaging the walls of the container 11.

The dam 15 may have several different shapes. For example in Fig. 1, the dam consists of a tubular member having a triangular section and made of an heat-resistant or refractory material such as ignited soap stone, sometimes termed "lava"; or of a similar hard inert and heat-insulating material, provided only that the same is of a nature that will not react with the mercury, nor cause the contamination of the latter or deterioration of the contactor. Preferably, also, the material constituting the dam should be non-wettable by mercury, and should be slightly roughened

so that the mercury will pass rapidly over the same without in any way adhering to it.

As illustrated in Figs. 1 and 2, the tubular dam is kept in place within the container 11 by being provided with one or more cylindrical springs 16, or other suitable resilient material serving as a "packing", disposed in the grooves 17 in the dam 15; as more clearly shown in the elevational view in Fig. 3. These springs are split at their ends, somewhat after the fashion of a piston ring. In placing the dam 15 within the container 11, the springs 16 are placed into the grooves 17, are then compressed so that they lie totally within the groove, whereupon the entire assembly is pushed into the glass container. The natural resilience of the springs 16 will hold the dam 15 in whatever position it has been placed in. If the springs are made of suitable material, such as being covered with iron, platinum, or made of chromium steel or nickel or tungsten, this will be satisfactory, as these materials are not adversely affected by the mercury.

The electrodes 12 and 13 are preferably made of a metal or other conducting substance that does not chemically react with the mercury. This may be pure tungsten; or iron; or iron alloyed with chromium, or any metal which exhibits substantially no tendency to amalgamate with the mercury or contaminate the mercury. The lead-in wires should be of such composition that a tight seal with the glass walls of the container is secured. "Dumet" wire, which is very suitable for the purpose, may be used for the lead in, but it should be understood that none of this "Dumet" wire must be exposed on the inside of the glass container, as the copper coating upon the same would amalgamate with and contaminate the mercury. Preferably, pure iron is used for the electrodes 12 and 13. The materials entering in the construction of my present contactor and the method of connecting the electrodes to the leading-in conductors, sealed in the walls of the container, may be those described respectively in U. S. Patents No. 1,598,874 and No. 1,598,875.

Referring to Figs. 1 and 2, it will be seen that electrode 13 extends for a considerable distance into the tubular dam 15, so that irrespective of the position of the tube, within reasonable limits, the mercury will be in contact with the electrode 13. This ensures that the electric arc will always occur upon the dam 15. In Fig. 1 the electrodes 12 and 13 are shown entering the tube from the top, but they may also enter from the bottom, as shown in Figs. 2 and 4.

An alternative construction is shown in Fig. 4. In this case the dam 15, which consists of a tubular member of heat-insulating material, is supported within the glass container 11 by means of a suitable cement. It

is desirable that such cement have a coefficient of expansion approximately the same as that of the material composing the container, as otherwise the alternate heating and cooling of the dam may cause the container or the dam to crack by reason of the strain produced by unequal expansion of the container and the dam.

An appropriate cement for the purpose, when the container 11 is made of glass and the dam 15 is made of a good grade of porcelain may comprise a mixture of aluminum oxide, asbestos and sodium silicate, otherwise known as waterglass. A suitable formula is:

Aluminum oxide, Al_2O_3 -----	Parts	30
Asbestos powder, $Mg_3Si_2O_7 \cdot 7H_2O$ -----	70	
Sodium silicate, $Na_2Si_4O_9$, sufficient to		
make a syrup-like paste.		

The nearer the coefficient of expansion of the glass is to that of the porcelain dam, the less asbestos is to be used in the above formula. Magnesium silicate, $MgSiO_3$, magnesium oxide, MgO , may replace the asbestos. The sodium silicate may also be diluted with some water before use. Another cement that has proven satisfactory is one made up of a mixture of lead phosphate, $Pb_3(PO_4)_2$ and sodium silicate. This is especially desirable when the glass employed has a high coefficient of expansion.

A further modification of my present contactor is that shown in Figs. 5 and 6. In this case the dam consists of a split tube of insulating material that will exhibit sufficient resiliency so that when longitudinally cut open, as shown in cross-section in Fig. 5, it will tend to expand slightly, so that it will hold itself in place when compressed, inserted into the tubular container, and then allowed to expand itself against the inside walls of the container. This will obviate the necessity of using any cement, and also will allow for expansion and contraction of the walls of the container.

Still another modification of my present invention is that shown in Fig. 7. In this case the dam 15, instead of being in the form of a tube, is a suitably shaped piece of refractory material of such contour that it will allow of cementing to the bottom of the container 11 by means of a cement such as already described herein. To ensure that the body of mercury will break rapidly and substantially at the same point at each make and break, a protrusion 15-a on the insulating material 15 is provided.

In order to cause a larger amount of mercury to be retained in contact with the electrode 12, the container 11 may be expanded and thus made deeper at the point 11-a (in Fig. 8), and the dam may consist (as shown in Fig. 9) of a tubular member 15 also hav-

ing an annular projection 15-a; although the construction of the dam may be similar to that shown in Fig. 7. The electrode 13 is so shaped and disposed that the end of the same extends for a distance into or upon the dam 15, this feature being characteristic of all of the specific constructions shown herein.

Wherever the springs 16 are not shown, the dam 15 is either held in place by its own resilience and by being split, or is held to the container by means of one of the cements, or their equivalent, as herein disclosed.

After the dam, electrodes and mercury have been placed in the container 11, the same is evacuated of all gases therein contained, and then the container is filled with hydrogen, or similar inert gas, so that the container will house no gas capable of oxidizing or of otherwise deleteriously reacting with the mercury or any of the materials within the container. The pressure of this gas may be equal to that of the atmosphere, or be subatmospheric or even at more than atmospheric pressure.

Some of the advantages accruing from the improved construction of my present invention are as follows:

In the first place the make and break in the electrical circuit occurs between mobile masses of mercury, and not between solid electrodes and mercury; second, any heat produced by the electric arcs obtaining at the point of break is kept away from the walls of the container, so that the latter will not be liable to fracture by sudden expansion; third, only a slight tilting of the container is necessary to effect the make or break; fourth, both bodies of mercury are always in direct metallic contact with the electrodes so that at no time is there any possibility of any arc forming between anything but mercury and mercury; fifth, by reason of the inclined sides of the dam, as shown in Figs. 1, 2, 4, 5, and 7, the break will be sudden and the mercury will roll away after such break, or, as shown in Figs. 7 and 8, the break will occur at a point where the mercury is very thin by reason of the projection 15-a; and, sixth, by reason of the electrode 13 terminating within the area of the dam 15, it is assured that the circuit will always be broken, under normal operating conditions, over the highly refractory and heat resistant material composing the dam 15.

By virtue of the construction of the electrical contactors described in the present application, it is possible to employ them for regulating electrical apparatus that requires comparatively heavy current where strong arcing occurs.

The types of contactors as above described form a very reliable means for controlling

electrical circuits carrying substantial currents at comparatively high voltages, without deterioration. Such a device obviously has a great many advantages over any former type of liquid contactor, since very little energy is required to tilt the contactor into and out of circuit-making and circuit-breaking positions, and, at the same time, the device is designed to be placed directly in series with the electrical apparatus controlled thereby.

While there have been shown and described several embodiments of the present invention, it is to be understood that many modifications may be made therein without departing from the spirit and scope of the appended claims, and I desire that only such limitations shall be imposed upon this invention as are specifically pointed out in the 10 claims and such as are required by the prior art.

Having thus described the invention, what is claimed, as new and desired to be secured by Letters Patent in the United States, is:—

25 1. In an electrical contactor of the type described, a refractory dam consisting of a split tapering walled tube of refractory material.

2. In an electrical contactor of the type described, a dam consisting of a split tube of refractory material.

3. In an electrical contactor of the type described, a dam consisting of a split tube of refractory material not adversely affected 35 by mercury, said dam being cemented to the walls of the container.

4. A tiltable electrical contactor comprising an hermetically sealed container, electrodes spaced apart within said container, 40 a dam consisting of a split tube of refractory material between said electrodes, a body of metallic conducting fluid, and an atmosphere of gas housed within said container.

45 5. A tiltable electrical contactor comprising an hermetically sealed container, electrodes spaced apart within said container, a dam consisting of a split tube of refractory material not adversely affected by mercury in said container and disposed between said 50 electrodes, a body of mercury adapted to establish a path for electric current between said electrodes and of sufficient quantity to cover said dam when the contactor is tipped into conducting position, and an atmosphere of hydrogen within said container.

55 6. A tiltable electrical contactor comprising an hermetically sealed glass container, metallic electrodes of a material not adversely affected by mercury spaced apart within 60 said container, a dam consisting of a split tube of refractory material nonwettable by mercury disposed in said container between said electrodes, a body of mercury adapted to connect electrically said electrodes and of sufficient quantity to cover said dam when

the contactor is tipped into conducting position, and an atmosphere of a gas inert to mercury within said container.

In witness whereof, I have hereunto subscribed my name.

LOUIS A. M. PHELAN.
